UNITED STATES PATENT OFFICE.

EDWIN B. STIMPSON, OF BROOKLYN, NEW YORK.

DESIGN FOR A STRAP.

SPECIFICATION forming part of Design No. 18,789, dated December 4, 1888.

Application filed October 30, 1888. Serial No. 289,563. Term of patent 7 years.

To all whom it may concern:

Be it known that I, EDWIN B. STIMPSON, of Brooklyn, in the county of Kings and State of New York, have invented and produced a 5 new and original Design for a Strap, of which the following is a specification.

I will describe my design for straps in detail, and then point out the novel features in a claim.

10 The accompanying drawing illustrates a strap showing my design.

This strap is shown as having approximately parallel side edges. Near each of these side edges is delineated a band, *a*, extending 15 lengthwise of the strap and intermediate of the bands *a*, and also extending lengthwise of

the strap is a band, *b*. The bands *a* *b* are each composed of parallel lines *c*, which extend at right angles to the direction of the lengths of the bands. 20

What I claim as my design is—

The design for a strap having parallel side edges and a surface ornamentation consisting of the bands *a* and intermediate band, *b*, said bands being composed of substantially 25 parallel lines *c*, substantially as shown and described.

EDWIN B. STIMPSON.
